UNITED STATES PATENT OFFICE

164,899

EXECUTIVE POSTURE SWIVEL CHAIR

John S. Burdick, North Muskegon, Mich., assignor to The Shaw-Walker Company, Muskegon, Mich., a corporation of Michigan

Application September 7, 1950, Serial No. 12,085

Term of patent 14 years

(Cl. D15—1)

To all whom it may concern:

Be it known that I, John S. Burdick, a citizen of the United States, residing at North Muskegon, in the county of Muskegon, State of Michigan, have invented a new, original, and ornamental Design for an Executive Posture Swivel Chair, of which the following is a specification, reference being made to the accompanying drawings, forming part thereof, wherein:

Figure 1 is a front view of an executive posture swivel chair, showing my new design;

Figure 2 is a side view of an executive posture swivel chair, showing my new design;

Figure 3 is a three-quarter front view of an executive posture swivel chair, showing my new design; and

Figure 4 is a rear view of an executive posture swivel chair, showing my new design.

The drawing is shaded to show contrasting appearance.

I claim:

The ornamental design for an executive posture swivel chair, as shown and described.

JOHN S. BURDICK.
